BATHTUB SEAT

David R. Hefley, Buckeye, Ariz.

Application August 30, 1957, Serial No. 681,347

3 Claims. (Cl. 4—185)

This invention relates to bathtub attachments, and more particularly to a bathtub seat attachment.

The main object of the invention is to provide a novel and improved bathtub seat attachment which is simple in construction, which is easy to install, and which is easy to adjust.

A further object of the invention is to provide an improved bathtub seat attachment which is inexpensive to manufacture, which is durable in construction, which is readily adjustable so that the seat board portion thereof may be placed in any desired position with relation to the wall of the bathtub on which the attachment is mounted, and which may be securely mounted on the bathtub wall without any danger of causing damage to the bathtub.

A still further object of the invention is to provide an improved bathtub seat attachment which includes safety hand rail elements, facilitating the entry of a person into the bathtub or leaving the bathtub, and serving to reduce hazards of injury from slipping or falling.

Further objects and advantages of the invention will become apparent from the following description and claims, and from the accompanying drawings, wherein:

Figure 1 is a perspective view of an improved bathtub seat attachment constructed in accordance with the present invention, and shown mounted on a bathtub wall, the bathtub wall being illustrated in dotted view.

Figure 2 is a fragmentary cross-sectional view taken on the line 2—2 of Figure 1.

Figure 3 is a horizontal cross-sectional view taken on the line 3—3 of Figure 2.

Figure 4 is an enlarged vertical cross-sectional detailed view taken on the line 4—4 of Figure 2.

Figure 5 is a fragmentary perspective view on a corner portion of the bathtub seat attachment of Figures 1 to 4, parts of the seat attachment being broken away and being in cross section to illustrate the details of construction.

Referring to the drawings, 11 generally designates a bathtub seat attachment according to this invention. Said attachment comprises a pair of vertical side frames 12, 12, said side frames being of inverted U-shaped configuration, and having resilient depending legs 13, 13, shaped to fit over the wall 14 of a conventional bathtub. The intermediate portions of the legs 13, 13 are connected together by the provision of a clamping bolt 15 pressing through one of the legs and threadedly engaged in an internally threaded sleeve member 16 threadedly secured to the opposing leg, whereby the legs 13, 13 may be flexed inwardly toward each other by tightening the bolt 15. The bolt 15 and sleeve portion 16 are covered by a suitable tubular sheathing of resiliently deformable material, such as rubber tubing or the like, to prevent damage to the top surface of the bathtub wall 14 on which the attachment is mounted. Said resiliently deformable sheathing is illustrated at 17 in Figure 2.

The inwardly opposing portions of the legs 13 are provided with spaced bumper elements 18 of resiliently

2

deformable material, such as rubber or the like, engageable with the respective opposite surfaces of the bathtub wall 14, and being resiliently deformable to prevent marring of said bathtub surfaces.

- 5 Secured on the upper portions of the legs 13, above the bolt 15 and sleeve 16 of each side frame 12 are clamping straps 19, 19 which are clampingly secured to the associated legs 13 as by clamping bolts 20 passing through the end portions of the straps, the intermediate portions of said straps surrounding the legs 13, as is clearly shown in Figure 5. Secured to the end portions of the straps are the respective angle brackets 21, said angle brackets projecting inwardly and being formed at their ends with vertical flanges 22 terminating at their top ends with horizontally extending arms 23 which are spaced above the top edges of the angle bars 21 and straps 19 by sufficient distance to receive the horizontal flange 24 of a seat board supporting bracket 25, as will be presently described.
- 10 Designated at 26 is a generally rectangular seat board which is provided at its opposite end edges with depending flanges 27 and at its longitudinal side edges with depending flanges 28. Secured to the inside surfaces of the flanges 28 are the angle bars 25, previously mentioned, with horizontal flanges 24 which are slidably received between the arms 23 and the top edges of angle brackets 21 and straps 19, as shown in Figure 5. Thus, the arms 23 and the angle brackets 21 and straps 19 define guide means on the side frames 12 engageable with the flange portions 24 on the seat board and guiding said seat board for horizontal adjustment between the side frames 12, 12, preventing the seat boards from moving vertically.
- 15 As shown in Figure 3, the ends 29 of the flanges 24 are spaced inwardly from the respective depending end flanges 27 so that the seat board may be at times disengaged from the side frames if so desired.
- 20 The respective bracket members 25 are formed at their ends with the arms 30 extending parallel to the adjacent depending seat board end flanges 27, and hinged to the arms 30 adjacent the junctions of the arms 30 with the main portions of the members 25 are respective locking plates 31. The longitudinal edges of the locking plates 31 are fastened to hinge pins 32 which are pivoted at their opposite ends to the arms 30 so that the locking plates are pivotally connected to the arms 30 adjacent the underside of the seat board on axes parallel to the vertical planes of the respective side frames 12. The free edges of the locking plates 31 are formed with the spaced notches 33 adapted to lockingly engage with the upwardly retaining arms 23 of the flanges 22, whereby to lock the seat board 26 against horizontal movement between the side frames 12, 12.
- 25 The ends of the locking plates 31 are formed with the lever portions 34 formed at their ends with the finger tabs 35, whereby the portions 34 may be readily manipulated to rotate the locking plates 31, whenever desired. As shown in Figure 5, the levers 34 extend beneath the seat board 26 and normally project below the plane of the seat board by a sufficient distance to be easily reached by a person desiring to release the seat board.
- 30 Pivoted at 36 to the end portion of each arm 30 at its inside surface is a retaining lever 37 carrying a weight 38 at its free end, the retaining lever 37 being provided at its intermediate portion with an inwardly projecting lug 39 overlying the top edge of the adjacent release lever 34, and being engageable with the top edge of the release lever to normally prevent the associated locking plate 31 from being rotated upwardly to unlocking position.
- 35 However, the weighted lever 37 is readily yieldable responsive to manual upward force exerted on the subjacent release lever 34, to allow the associated locking

- 40 45 50 55 60 65 70
- lever 34 to be rotated upwardly to unlock the seat board 26. The lever 34 is formed with a slot 40 in its upper portion, the slot 40 being defined by a pair of parallel side walls 41, 41 and a bottom wall 42, the slot 40 being open at its top end and closed at its bottom end by a stop 43. The slot 40 is formed with a shoulder 44 at its top end, the shoulder 44 being defined by a pair of parallel side walls 45, 45 and a top wall 46, the shoulder 44 being located at a distance from the top end of the slot 40 which is sufficient to allow the lever 34 to be rotated upwardly to unlock the seat board 26. The shoulder 44 is formed with a slot 47 in its top surface, the slot 47 being defined by a pair of parallel side walls 48, 48 and a top wall 49, the slot 47 being open at its top end and closed at its bottom end by a stop 50. The slot 47 is formed with a shoulder 51 at its top end, the shoulder 51 being defined by a pair of parallel side walls 52, 52 and a top wall 53, the shoulder 51 being located at a distance from the top end of the slot 47 which is sufficient to allow the lever 34 to be rotated upwardly to unlock the seat board 26. The shoulder 51 is formed with a slot 54 in its top surface, the slot 54 being defined by a pair of parallel side walls 55, 55 and a top wall 56, the slot 54 being open at its top end and closed at its bottom end by a stop 57. The slot 54 is formed with a shoulder 58 at its top end, the shoulder 58 being defined by a pair of parallel side walls 59, 59 and a top wall 60, the shoulder 58 being located at a distance from the top end of the slot 54 which is sufficient to allow the lever 34 to be rotated upwardly to unlock the seat board 26. The shoulder 58 is formed with a slot 61 in its top surface, the slot 61 being defined by a pair of parallel side walls 62, 62 and a top wall 63, the slot 61 being open at its top end and closed at its bottom end by a stop 64. The slot 61 is formed with a shoulder 65 at its top end, the shoulder 65 being defined by a pair of parallel side walls 66, 66 and a top wall 67, the shoulder 65 being located at a distance from the top end of the slot 61 which is sufficient to allow the lever 34 to be rotated upwardly to unlock the seat board 26. The shoulder 65 is formed with a slot 68 in its top surface, the slot 68 being defined by a pair of parallel side walls 69, 69 and a top wall 70, the slot 68 being open at its top end and closed at its bottom end by a stop 71. The slot 68 is formed with a shoulder 72 at its top end, the shoulder 72 being defined by a pair of parallel side walls 73, 73 and a top wall 74, the shoulder 72 being located at a distance from the top end of the slot 68 which is sufficient to allow the lever 34 to be rotated upwardly to unlock the seat board 26. The shoulder 72 is formed with a slot 75 in its top surface, the slot 75 being defined by a pair of parallel side walls 76, 76 and a top wall 77, the slot 75 being open at its top end and closed at its bottom end by a stop 78. The slot 75 is formed with a shoulder 79 at its top end, the shoulder 79 being defined by a pair of parallel side walls 80, 80 and a top wall 81, the shoulder 79 being located at a distance from the top end of the slot 75 which is sufficient to allow the lever 34 to be rotated upwardly to unlock the seat board 26. The shoulder 79 is formed with a slot 82 in its top surface, the slot 82 being defined by a pair of parallel side walls 83, 83 and a top wall 84, the slot 82 being open at its top end and closed at its bottom end by a stop 85. The slot 82 is formed with a shoulder 86 at its top end, the shoulder 86 being defined by a pair of parallel side walls 87, 87 and a top wall 88, the shoulder 86 being located at a distance from the top end of the slot 82 which is sufficient to allow the lever 34 to be rotated upwardly to unlock the seat board 26. The shoulder 86 is formed with a slot 89 in its top surface, the slot 89 being defined by a pair of parallel side walls 90, 90 and a top wall 91, the slot 89 being open at its top end and closed at its bottom end by a stop 92. The slot 89 is formed with a shoulder 93 at its top end, the shoulder 93 being defined by a pair of parallel side walls 94, 94 and a top wall 95, the shoulder 93 being located at a distance from the top end of the slot 89 which is sufficient to allow the lever 34 to be rotated upwardly to unlock the seat board 26. The shoulder 93 is formed with a slot 96 in its top surface, the slot 96 being defined by a pair of parallel side walls 97, 97 and a top wall 98, the slot 96 being open at its top end and closed at its bottom end by a stop 99. The slot 96 is formed with a shoulder 100 at its top end, the shoulder 100 being defined by a pair of parallel side walls 101, 101 and a top wall 102, the shoulder 100 being located at a distance from the top end of the slot 96 which is sufficient to allow the lever 34 to be rotated upwardly to unlock the seat board 26. The shoulder 100 is formed with a slot 103 in its top surface, the slot 103 being defined by a pair of parallel side walls 104, 104 and a top wall 105, the slot 103 being open at its top end and closed at its bottom end by a stop 106. The slot 103 is formed with a shoulder 107 at its top end, the shoulder 107 being defined by a pair of parallel side walls 108, 108 and a top wall 109, the shoulder 107 being located at a distance from the top end of the slot 103 which is sufficient to allow the lever 34 to be rotated upwardly to unlock the seat board 26. The shoulder 107 is formed with a slot 110 in its top surface, the slot 110 being defined by a pair of parallel side walls 111, 111 and a top wall 112, the slot 110 being open at its top end and closed at its bottom end by a stop 113. The slot 110 is formed with a shoulder 114 at its top end, the shoulder 114 being defined by a pair of parallel side walls 115, 115 and a top wall 116, the shoulder 114 being located at a distance from the top end of the slot 110 which is sufficient to allow the lever 34 to be rotated upwardly to unlock the seat board 26. The shoulder 114 is formed with a slot 117 in its top surface, the slot 117 being defined by a pair of parallel side walls 118, 118 and a top wall 119, the slot 117 being open at its top end and closed at its bottom end by a stop 120. The slot 117 is formed with a shoulder 121 at its top end, the shoulder 121 being defined by a pair of parallel side walls 122, 122 and a top wall 123, the shoulder 121 being located at a distance from the top end of the slot 117 which is sufficient to allow the lever 34 to be rotated upwardly to unlock the seat board 26. The shoulder 121 is formed with a slot 124 in its top surface, the slot 124 being defined by a pair of parallel side walls 125, 125 and a top wall 126, the slot 124 being open at its top end and closed at its bottom end by a stop 127. The slot 124 is formed with a shoulder 128 at its top end, the shoulder 128 being defined by a pair of parallel side walls 129, 129 and a top wall 130, the shoulder 128 being located at a distance from the top end of the slot 124 which is sufficient to allow the lever 34 to be rotated upwardly to unlock the seat board 26. The shoulder 128 is formed with a slot 131 in its top surface, the slot 131 being defined by a pair of parallel side walls 132, 132 and a top wall 133, the slot 131 being open at its top end and closed at its bottom end by a stop 134. The slot 131 is formed with a shoulder 135 at its top end, the shoulder 135 being defined by a pair of parallel side walls 136, 136 and a top wall 137, the shoulder 135 being located at a distance from the top end of the slot 131 which is sufficient to allow the lever 34 to be rotated upwardly to unlock the seat board 26. The shoulder 135 is formed with a slot 138 in its top surface, the slot 138 being defined by a pair of parallel side walls 139, 139 and a top wall 140, the slot 138 being open at its top end and closed at its bottom end by a stop 141. The slot 138 is formed with a shoulder 142 at its top end, the shoulder 142 being defined by a pair of parallel side walls 143, 143 and a top wall 144, the shoulder 142 being located at a distance from the top end of the slot 138 which is sufficient to allow the lever 34 to be rotated upwardly to unlock the seat board 26. The shoulder 142 is formed with a slot 145 in its top surface, the slot 145 being defined by a pair of parallel side walls 146, 146 and a top wall 147, the slot 145 being open at its top end and closed at its bottom end by a stop 148. The slot 145 is formed with a shoulder 149 at its top end, the shoulder 149 being defined by a pair of parallel side walls 150, 150 and a top wall 151, the shoulder 149 being located at a distance from the top end of the slot 145 which is sufficient to allow the lever 34 to be rotated upwardly to unlock the seat board 26. The shoulder 149 is formed with a slot 154 in its top surface, the slot 154 being defined by a pair of parallel side walls 155, 155 and a top wall 156, the slot 154 being open at its top end and closed at its bottom end by a stop 157. The slot 154 is formed with a shoulder 158 at its top end, the shoulder 158 being defined by a pair of parallel side walls 159, 159 and a top wall 160, the shoulder 158 being located at a distance from the top end of the slot 154 which is sufficient to allow the lever 34 to be rotated upwardly to unlock the seat board 26. The shoulder 158 is formed with a slot 161 in its top surface, the slot 161 being defined by a pair of parallel side walls 162, 162 and a top wall 163, the slot 161 being open at its top end and closed at its bottom end by a stop 164. The slot 161 is formed with a shoulder 165 at its top end, the shoulder 165 being defined by a pair of parallel side walls 166, 166 and a top wall 167, the shoulder 165 being located at a distance from the top end of the slot 161 which is sufficient to allow the lever 34 to be rotated upwardly to unlock the seat board 26. The shoulder 165 is formed with a slot 168 in its top surface, the slot 168 being defined by a pair of parallel side walls 169, 169 and a top wall 170, the slot 168 being open at its top end and closed at its bottom end by a stop 171. The slot 168 is formed with a shoulder 172 at its top end, the shoulder 172 being defined by a pair of parallel side walls 173, 173 and a top wall 174, the shoulder 172 being located at a distance from the top end of the slot 168 which is sufficient to allow the lever 34 to be rotated upwardly to unlock the seat board 26. The shoulder 172 is formed with a slot 177 in its top surface, the slot 177 being defined by a pair of parallel side walls 178, 178 and a top wall 179, the slot 177 being open at its top end and closed at its bottom end by a stop 180. The slot 177 is formed with a shoulder 181 at its top end, the shoulder 181 being defined by a pair of parallel side walls 182, 182 and a top wall 183, the shoulder 181 being located at a distance from the top end of the slot 177 which is sufficient to allow the lever 34 to be rotated upwardly to unlock the seat board 26. The shoulder 181 is formed with a slot 186 in its top surface, the slot 186 being defined by a pair of parallel side walls 187, 187 and a top wall 188, the slot 186 being open at its top end and closed at its bottom end by a stop 189. The slot 186 is formed with a shoulder 190 at its top end, the shoulder 190 being defined by a pair of parallel side walls 191, 191 and a top wall 192, the shoulder 190 being located at a distance from the top end of the slot 186 which is sufficient to allow the lever 34 to be rotated upwardly to unlock the seat board 26. The shoulder 190 is formed with a slot 195 in its top surface, the slot 195 being defined by a pair of parallel side walls 196, 196 and a top wall 197, the slot 195 being open at its top end and closed at its bottom end by a stop 198. The slot 195 is formed with a shoulder 199 at its top end, the shoulder 199 being defined by a pair of parallel side walls 200, 200 and a top wall 201, the shoulder 199 being located at a distance from the top end of the slot 195 which is sufficient to allow the lever 34 to be rotated upwardly to unlock the seat board 26. The shoulder 199 is formed with a slot 204 in its top surface, the slot 204 being defined by a pair of parallel side walls 205, 205 and a top wall 206, the slot 204 being open at its top end and closed at its bottom end by a stop 207. The slot 204 is formed with a shoulder 208 at its top end, the shoulder 208 being defined by a pair of parallel side walls 209, 209 and a top wall 210, the shoulder 208 being located at a distance from the top end of the slot 204 which is sufficient to allow the lever 34 to be rotated upwardly to unlock the seat board 26. The shoulder 208 is formed with a slot 213 in its top surface, the slot 213 being defined by a pair of parallel side walls 214, 214 and a top wall 215, the slot 213 being open at its top end and closed at its bottom end by a stop 216. The slot 213 is formed with a shoulder 217 at its top end, the shoulder 217 being defined by a pair of parallel side walls 218, 218 and a top wall 219, the shoulder 217 being located at a distance from the top end of the slot 213 which is sufficient to allow the lever 34 to be rotated upwardly to unlock the seat board 26. The shoulder 217 is formed with a slot 222 in its top surface, the slot 222 being defined by a pair of parallel side walls 223, 223 and a top wall 224, the slot 222 being open at its top end and closed at its bottom end by a stop 225. The slot 222 is formed with a shoulder 226 at its top end, the shoulder 226 being defined by a pair of parallel side walls 227, 227 and a top wall 228, the shoulder 226 being located at a distance from the top end of the slot 222 which is sufficient to allow the lever 34 to be rotated upwardly to unlock the seat board 26. The shoulder 226 is formed with a slot 231 in its top surface, the slot 231 being defined by a pair of parallel side walls 232, 232 and a top wall 233, the slot 231 being open at its top end and closed at its bottom end by a stop 234. The slot 231 is formed with a shoulder 235 at its top end, the shoulder 235 being defined by a pair of parallel side walls 236, 236 and a top wall 237, the shoulder 235 being located at a distance from the top end of the slot 231 which is sufficient to allow the lever 34 to be rotated upwardly to unlock the seat board 26. The shoulder 235 is formed with a slot 240 in its top surface, the slot 240 being defined by a pair of parallel side walls 241, 241 and a top wall 242, the slot 240 being open at its top end and closed at its bottom end by a stop 243. The slot 240 is formed with a shoulder 244 at its top end, the shoulder 244 being defined by a pair of parallel side walls 245, 245 and a top wall 246, the shoulder 244 being located at a distance from the top end of the slot 240 which is sufficient to allow the lever 34 to be rotated upwardly to unlock the seat board 26. The shoulder 244 is formed with a slot 249 in its top surface, the slot 249 being defined by a pair of parallel side walls 250, 250 and a top wall 251, the slot 249 being open at its top end and closed at its bottom end by a stop 252. The slot 249 is formed with a shoulder 253 at its top end, the shoulder 253 being defined by a pair of parallel side walls 254, 254 and a top wall 255, the shoulder 253 being located at a distance from the top end of the slot 249 which is sufficient to allow the lever 34 to be rotated upwardly to unlock the seat board 26. The shoulder 253 is formed with a slot 258 in its top surface, the slot 258 being defined by a pair of parallel side walls 259, 259 and a top wall 260, the slot 258 being open at its top end and closed at its bottom end by a stop 261. The slot 258 is formed with a shoulder 262 at its top end, the shoulder 262 being defined by a pair of parallel side walls 263, 263 and a top wall 264, the shoulder 262 being located at a distance from the top end of the slot 258 which is sufficient to allow the lever 34 to be rotated upwardly to unlock the seat board 26. The shoulder 262 is formed with a slot 267 in its top surface, the slot 267 being defined by a pair of parallel side walls 268, 268 and a top wall 269, the slot 267 being open at its top end and closed at its bottom end by a stop 270. The slot 267 is formed with a shoulder 271 at its top end, the shoulder 271 being defined by a pair of parallel side walls 272, 272 and a top wall 273, the shoulder 271 being located at a distance from the top end of the slot 267 which is sufficient to allow the lever 34 to be rotated upwardly to unlock the seat board 26. The shoulder 271 is formed with a slot 276 in its top surface, the slot 276 being defined by a pair of parallel side walls 277, 277 and a top wall 278, the slot 276 being open at its top end and closed at its bottom end by a stop 279. The slot 276 is formed with a shoulder 280 at its top end, the shoulder 280 being defined by a pair of parallel side walls 281, 281 and a top wall 282, the shoulder 280 being located at a distance from the top end of the slot 276 which is sufficient to allow the lever 34 to be rotated upwardly to unlock the seat board 26. The shoulder 280 is formed with a slot 285 in its top surface, the slot 285 being defined by a pair of parallel side walls 286, 286 and a top wall 287, the slot 285 being open at its top end and closed at its bottom end by a stop 288. The slot 285 is formed with a shoulder 289 at its top end, the shoulder 289 being defined by a pair of parallel side walls 290, 290 and a top wall 291, the shoulder 289 being located at a distance from the top end of the slot 285 which is sufficient to allow the lever 34 to be rotated upwardly to unlock the seat board 26. The shoulder 289 is formed with a slot 294 in its top surface, the slot 294 being defined by a pair of parallel side walls 295, 295 and a top wall 296, the slot 294 being open at its top end and closed at its bottom end by a stop 297. The slot 294 is formed with a shoulder 298 at its top end, the shoulder 298 being defined by a pair of parallel side walls 299, 299 and a top wall 300, the shoulder 298 being located at a distance from the top end of the slot 294 which is sufficient to allow the lever 34 to be rotated upwardly to unlock the seat board 26. The shoulder 298 is formed with a slot 303 in its top surface, the slot 303 being defined by a pair of parallel side walls 304, 304 and a top wall 305, the slot 303 being open at its top end and closed at its bottom end by a stop 306. The slot 303 is formed with a shoulder 307 at its top end, the shoulder 307 being defined by a pair of parallel side walls 308, 308 and a top wall 309, the shoulder 307 being located at a distance from the top end of the slot 303 which is sufficient to allow the lever 34 to be rotated upwardly to unlock the seat board 26. The shoulder 307 is formed with a slot 312 in its top surface, the slot 312 being defined by a pair of parallel side walls 313, 313 and a top wall 314, the slot 312 being open at its top end and closed at its bottom end by a stop 315. The slot 312 is formed with a shoulder 316 at its top end, the shoulder 316 being defined by a pair of parallel side walls 317, 317 and a top wall 318, the shoulder 316 being located at a distance from the top end of the slot 312 which is sufficient to allow the lever 34 to be rotated upwardly to unlock the seat board 26. The shoulder 316 is formed with a slot 321 in its top surface, the slot 321 being defined by a pair of parallel side walls 322, 322 and a top wall 323, the slot 321 being open at its top end and closed at its bottom end by a stop 324. The slot 321 is formed with a shoulder 325 at its top end, the shoulder 325 being defined by a pair of parallel side walls 326, 326 and a top wall 327, the shoulder 325 being located at a distance from the top end of the slot 321 which is sufficient to allow the lever 34 to be rotated upwardly to unlock the seat board 26. The shoulder 325 is formed with a slot 330 in its top surface, the slot 330 being defined by a pair of parallel side walls 331, 331 and a top wall 332, the slot 330 being open at its top end and closed at its bottom end by a stop 333. The slot 330 is formed with a shoulder 334 at its top end, the shoulder 334 being defined by a pair of parallel side walls 335, 335 and a top wall 336, the shoulder 334 being located at a distance from the top end of the slot 330 which is sufficient to allow the lever 34 to be rotated upwardly to unlock the seat board 26. The shoulder 334 is formed with a slot 339 in its top surface, the slot 339 being defined by a pair of parallel side walls 340, 340 and a top wall 341, the slot 339 being open at its top end and closed at its bottom end by a stop 342. The slot 339 is formed with a shoulder 343 at its top end, the shoulder 343 being defined by a pair of parallel side walls 344, 344 and a top wall 345, the shoulder 343 being located at a distance from the top end of the slot 339 which is sufficient to allow the lever 34 to be rotated upwardly to unlock the seat board 26. The shoulder 343 is formed with a slot 348 in its top surface, the slot 348 being defined by a pair of parallel side walls 349, 349 and a top wall 350, the slot 348 being open at its top end and closed at its bottom end by a stop 351. The slot 348 is formed with a shoulder 352 at its top end, the shoulder 352 being defined by a pair of parallel side walls 353, 353 and a top wall 354, the shoulder 352 being located at a distance from the top end of the slot 348 which is sufficient to allow the lever 34 to be rotated upwardly to unlock the seat board 26. The shoulder 352 is formed with a slot 357 in its top surface, the slot 357 being defined by a pair of parallel side walls 358, 358 and a top wall 359, the slot 357 being open at its top end and closed at its bottom end by a stop 360. The slot 357 is formed with a shoulder 361 at its top end, the shoulder 361 being defined by a pair of parallel side walls 362, 362 and a top wall 363, the shoulder 361 being located at a distance from the top end of the slot 357 which is sufficient to allow the lever 34 to be rotated upwardly to unlock the seat board 26. The shoulder 361 is formed with a slot 366 in its top surface, the slot 366 being defined by a pair of parallel side walls 367, 367 and a top wall 368, the slot 366 being open at its top end and closed at its bottom end by a stop 369. The slot 366 is formed with a shoulder 370 at its top end, the shoulder 370 being defined by a pair of parallel side walls 371, 371 and a top wall 372, the shoulder 370 being located at a distance from the top end of the slot 366 which is sufficient to allow the lever 34 to be rotated upwardly to unlock the seat board 26. The shoulder 370 is formed with a slot 375 in its top surface, the slot 375 being defined by a pair of parallel side walls 376, 376 and a top wall 377, the slot 375 being open at its top end and closed at its bottom end by a stop 378. The slot 375 is formed with a shoulder 379 at its top end, the shoulder 379 being defined by a pair of parallel side walls 380, 380 and a top wall 381, the shoulder 379 being located at a distance from the top end of the slot 375 which is sufficient to allow the lever 34 to be rotated upwardly to unlock the seat board 26. The shoulder 379 is formed with a slot 384 in its top surface, the slot 384 being defined by a pair of parallel side walls 385, 385 and a top wall 386, the slot 384 being open at its top end and closed at its bottom end by a stop 387. The slot 384 is formed with a shoulder 388 at its top end, the shoulder 388 being defined by a pair of parallel side walls 389, 389 and a top wall 390, the shoulder 388 being located at a distance from the top end of the slot 384 which is sufficient to allow the lever 34 to be rotated upwardly to unlock the seat board 26. The shoulder 388 is formed with a slot 393 in its top surface, the slot 393 being defined by a pair of parallel side walls 394, 394 and a top wall 395, the slot 393 being open at its top end and closed at its bottom end by a stop 396. The slot 393 is formed with a shoulder 397 at its top end, the shoulder 397 being defined by a pair of parallel side walls 398, 398 and a top wall 399, the shoulder 397 being located at a distance from the top end of the slot 393 which is sufficient to allow the lever 34 to be rotated upwardly to unlock the seat board 26. The shoulder 397 is formed with a slot 402 in its top surface, the slot 402 being defined by a pair of parallel side walls 403, 403 and a top wall 404, the slot 402 being open at its top end and closed at its bottom end by a stop 405. The slot 402 is formed with a shoulder 406 at its top end, the shoulder 406 being defined by a pair of parallel side walls 407, 407 and a top wall 408, the shoulder 406 being located at a distance from the top end of the slot 402 which is sufficient to allow the lever 34 to be rotated upwardly to unlock the seat board 26. The shoulder 406 is formed with a slot 411 in its top surface, the slot 411 being defined by a pair of parallel side walls 412, 412 and a top wall 413, the slot 411 being open at its top end and closed at its bottom end by a stop 414. The slot 411 is formed with a shoulder 415 at its top end, the shoulder 415 being defined by a pair of parallel side walls 416, 416 and a top wall 417, the shoulder 415 being located at a distance from the top end of the slot 411 which is sufficient to allow the lever 34 to be rotated upwardly to unlock the seat board 26. The shoulder 415 is formed with a slot 419 in its top surface, the slot 419 being defined by a pair of parallel side walls 420, 420 and a top wall 421, the slot 419 being open at its top end and closed at its bottom end by a stop 422. The slot 419 is formed with a shoulder 423 at its top end, the shoulder 423 being defined by a pair of parallel side walls 424, 424 and a top wall 425, the shoulder 423 being located at a distance from the top end of the slot 419 which is sufficient to allow the lever 34 to be rotated upwardly to unlock the seat board 26. The shoulder 423 is formed with a slot 428 in its top surface, the slot 428 being defined by a pair of parallel side walls 429, 429 and a top wall 430, the slot 428 being open at its top end and closed at its bottom end by a stop 431. The slot 428 is formed with a shoulder 432 at its top end, the shoulder 432 being defined by a pair of parallel side walls 433, 433 and a top wall 434, the shoulder 432 being located at a distance from the top end of the slot 428 which is sufficient to allow the lever 34 to be rotated upwardly to unlock the seat board 26. The shoulder 432 is formed with a slot 437 in its top surface, the slot 437 being defined by a pair of parallel side walls 438, 438 and a top wall 439, the slot 437 being open at its top end and closed at its bottom end by a stop 440. The slot 437 is formed with a shoulder 441 at its top end, the shoulder 441 being defined by a pair of parallel side walls 442, 442 and a top wall 443, the shoulder 441 being located at a distance from the top end of the slot 437 which is sufficient to allow the lever 34 to be rotated upwardly to unlock the seat board 26. The shoulder 441 is formed with a slot 446 in its top surface, the slot 446 being defined by a pair of parallel side walls 447, 447 and a top wall 448, the slot 446 being open at its top end and closed at its bottom end by a stop 449. The slot 446 is formed with a shoulder 450 at its top end, the shoulder 450 being defined by a pair of parallel side walls 451, 451 and a top wall 452, the shoulder 450 being located at a distance from the top end of the slot 446 which is sufficient to allow the lever 34 to be rotated upwardly to unlock the seat board 26. The shoulder 450 is formed with a slot 455 in its top surface, the slot 455 being defined by a pair of parallel side walls 456, 456 and a top wall 457, the slot 455 being open at its top end and closed at its bottom end by a stop 458. The slot 455 is formed with a shoulder 459 at its top end, the shoulder 459 being defined by a pair of parallel side walls 460, 460 and a top wall 461, the shoulder 459 being located at a distance from the top end of the slot 455 which is sufficient to allow the lever 34 to be rotated upwardly to unlock the seat board 26. The shoulder 459 is formed

plate 31 to be rotated upwardly toward unlocking position, whenever desired.

As will be readily apparent, the position of the spaced notches 33 along the free edges of the locking plates 31 allows the seat board 26 to be readily adjusted horizontally to a desired position between the side frames 12, 12, namely, to a position overlying the interior of the bathtub, overlying the top surface of the bathtub wall 14, or to a position extending laterally outwardly from the bathtub.

As will be further apparent, the seat board 26 may be readily removed for cleaning, whenever desired, by sliding same sufficiently so that the arms 23 clear the space between the ends 29 of the flanges 24 and the adjacent depending end flange 27, whereby the seat board may be disengaged from the side frames 12, 12 and removed for cleaning. The disassembly of the attachment may be further facilitated by loosening the bolts 20, whereby the arms 23 may be moved vertically downwardly through the space between the flange ends 29 and the adjacent depending flanges 27, whereby the flanges 24 may be disengaged from the arms 23.

The arcuate top ends of the side frames 12 serve as safety hand rail elements, facilitating the entry of a person into the bathtub or leaving the bathtub, and serving to reduce hazards of injury from slipping or falling while entering or leaving the bathtub.

While a specific embodiment of an improved bathtub seat attachment has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a bathtub seat, a pair of vertical side frames shaped to fit over the wall of a bathtub, a seat board adapted to be disposed horizontally between said side frames, guide means on the side frames slidably engageable with opposite side marginal portions of said seat board and being formed and arranged to guide said seat board for horizontal adjustment between said frames, and pivoted locking means on the seat board lockingly

engageable with said guide means to releasably secure said seat board in a horizontally adjusted position between said side frames.

2. In a bathtub seat, a pair of vertical side frames having resilient depending legs shaped to fit over the wall of a bathtub, clamping means on each frame connecting the legs thereof and being formed and arranged to flex said legs into clamping engagement with the wall of the bathtub, a seat board adapted to be disposed horizontally between said side frames, guide means on the side frames slidably engageable with opposite side marginal portions of said seat board and being formed and arranged to prevent said seat board from moving vertically and to guide said seat board for horizontal adjustment between said frames, and pivoted locking means on the seat board lockingly engageable with said guide means to releasably secure said seat board in a horizontally adjusted position between said side frames.

15 3. In a bathtub seat, a pair of vertical side frames having resilient depending legs shaped to fit over the wall of a bathtub, clamping means on each frame connecting the legs thereof and being formed and arranged to flex said legs into clamping engagement with the wall of the bathtub, a seat board adapted to be disposed horizontally between said side frames, guide means on the side frames slidably engageable with opposite side marginal portions of said seat board and being formed and arranged to prevent said seat board from moving vertically and to guide said seat board for horizontal adjustment between said frames, and pivoted locking means on the seat board lockingly engageable with said guide means to releasably secure said seat board in a horizontally adjusted position between said side frames.

20 4. In a bathtub seat, a pair of vertical side frames having resilient depending legs shaped to fit over the wall of a bathtub, clamping means on each frame connecting the legs thereof and being formed and arranged to flex said legs into clamping engagement with the wall of the bathtub, a seat board adapted to be disposed horizontally between said side frames, guide means on the side frames slidably engageable with opposite side marginal portions of said seat board and being formed and arranged to prevent said seat board from moving vertically and to guide said seat board for horizontal adjustment between said frames, and pivoted locking means on the seat board lockingly engageable with said guide means to releasably secure said seat board in a horizontally adjusted position between said side frames.

25 5. In a bathtub seat, a pair of vertical side frames having resilient depending legs shaped to fit over the wall of a bathtub, clamping means on each frame connecting the legs thereof and being formed and arranged to flex said legs into clamping engagement with the wall of the bathtub, a seat board adapted to be disposed horizontally between said side frames, guide means on the side frames slidably engageable with opposite side marginal portions of said seat board and being formed and arranged to prevent said seat board from moving vertically and to guide said seat board for horizontal adjustment between said frames, and pivoted locking means on the seat board lockingly engageable with said guide means to releasably secure said seat board in a horizontally adjusted position between said side frames.

30 6. In a bathtub seat, a pair of vertical side frames having resilient depending legs shaped to fit over the wall of a bathtub, clamping means on each frame connecting the legs thereof and being formed and arranged to flex said legs into clamping engagement with the wall of the bathtub, a seat board adapted to be disposed horizontally between said side frames, guide means on the side frames slidably engageable with opposite side marginal portions of said seat board and being formed and arranged to prevent said seat board from moving vertically and to guide said seat board for horizontal adjustment between said frames, and a locking plate pivotally connected at one edge to the underside of said seat board on an axis parallel to the vertical planes of the side frames and being formed at its free edge with spaced notches lockingly engageable with said guide means to releasably secure said seat board in a horizontally adjusted position between said side frames.
